CLAIM

We claim the ornamental design for a LED lamp module, as shown and described.

DESCRIPTION

FIG. 1 is a front perspective view of a LED lamp module according to our design;

FIG. 2 is a front view of the LED lamp module of FIG. 1;
FIG. 3 is a rear view of the LED lamp module of FIG. 1;
FIG. 4 is a left side view of the LED lamp module of FIG. 1;
FIG. 5 is a right side view of the LED lamp module of FIG. 1;
FIG. 6 is a top view of the LED lamp module of FIG. 1;
FIG. 7 is a bottom view of the LED lamp module of FIG. 1; and,

FIG. 8 is a front perspective view of the LED lamp module of FIG. 1 shown in use with the light emitting part in diagonal dash-dot lines.

The dash-dot lines shown in FIG. 8 to illustrate the light emitting part of the LED lamp module forms no part of the claimed design.
